UNITED STATES PATENT OFFICE.

JOHN WILLISON, OF CLEVELAND, OHIO, ASSIGNOR TO NATIONAL MALLEABLE AND STEEL CASTINGS COMPANY, OF CLEVELAND, OHIO, A CORPORATION OF OHIO.

CAR COUPLER.

Application filed March 17, 1924. Serial No. 699,657.

To all whom it may concern:

Be it known that I, JOHN WILLISON, a subject of the King of Great Britain, residing at Cleveland, Cuyahoga County, Ohio, have invented new and useful Improvements in Car Couplers, of which the following is a specification, reference being had to the accompanying drawings, in which—

Fig. 1 is a plan showing my invention with the transitional mechanism in use; Fig. 2 is a side elevation thereof; Fig. 3 is a plan similar to Fig. 1 but with the automatic coupler in coupling position; Fig. 4 is an enlarged horizontal section of the centering mechanism on lines IV—IV of Fig. 2, but with the parts in the position shown in Fig. 3; and Figs. 5 and 6 are sections on lines V—V and VI—VI of Fig. 4, respectively.

My invention relates to car couplers and is particularly designed to provide means for permitting cars equipped with automatic couplers to be coupled with cars equipped with couplers of other types such as of the drawhook and side buffer type. To this end a transitional or supplemental coupling device is provided which is attached to the automatic coupler and is so arranged that either the transitional device or the automatic coupler may be easily swung into or out of operative position and thereby be ready for coupling with an automatic coupler of the same type or with a draw-hook arrangement or other form of coupler. My invention also provides means whereby the automatic coupler is controlled by a spring centering device, and at the same time provision is made for a free lateral swing within the automatic coupling range of the automatic coupler. My invention also contains provision whereby when the transitional coupling is in use the automatic coupler centering means shall be rendered inoperative and remain in inoperative position until the automatic coupler is again moved back into its coupling range. My invention also comprises the various features which I shall hereinafter describe and claim.

Referring to the drawings, 2 indicates an automatic coupler of the rigid jawed type, such as is described in my Patent 1,201,665, dated October 17, 1916, the rearwardly extending shank 3 of which has near its rear end a vertical aperture 4 by which the coupler is secured to a draft casting 5 by a

pivot pin 6. Mounted on the rear of the 55 coupler head and resting on the shank 3 is a saddle-shaped transition member 7 having, preferably, integral therewith and extending to one side of the coupler head a hook 8. The forward face 9 of the transition member 7 bears against the rear face 10 of the coupler head, and extending forwardly from the transition member and on either side of the coupler head are a pair of ears 11, 12, which are apertured for reception of the securing pin 13, which extends through such ears and through the rear portion of the coupler head. The ear 12, on the side opposite the hook 8, preferably has an inward projection 14 which engages a 70 complementary projection 15 in the side of the coupler head and thereby assists in resisting the rotative stresses imposed upon the transition member by the off-centered application of force upon the hook 8 when 75 the transitional member 7 is in use. The transitional member 7 may also be arranged so that its rear side will, under severe buffing stresses imposed upon the automatic coupler, engage the forward face 80 of the coupler pocket 51 and thereby form a buffing stop.

The transitional member 7 is employed for coupling with a car equipped with a non-automatic coupler such as a coupling 85 16 of the draw hook type, in which event the coupling 16 is connected to the hook 8 by the shackle and slack adjuster 17, as is shown in Fig. 1.

The automatic coupler is free to move 90 without restraint in the normal coupling range indicated by the lines *a* and *b* in Fig. 3, but beyond such range its movement is controlled by a coupler centering device, which tends to return the coupler to 95 the normal coupling range when the coupler has been carried beyond such range by movement of the car on which the coupler is mounted around curves.

A coupler centering device suitable for the foregoing purpose comprises a base member 18 secured to one of the car sills 50, on which is formed the socket 19 for a bearing 20 of the spring lever 21. On the lever 21 are a pair of trunnions 22 which seat in apertures 23 of the links 24. The links 24 have slotted outer ends 25 which engage the lugs 26 of the outer follower 27. Bearing against

the inner face of the follower 27 is a spring 28 which surrounds the links 24 and at its inner end bears against the inner follower 29, which in turn bears against the shoulders 30 of the base member 18. Securing the parts of the centering device together is a through bolt 31, one end of which is anchored within the base member and extends outwardly inside the spring between the links 24 and through the outer follower 27, a nut 32 at the outer end having a bearing against the outer face 33 of the follower 27. The lever 21 at the end opposite its bearing in the socket 19 of the base member 18 has a horizontal slot 34 for the latch 35. The lever 21 has also a vertically extending slot 36 and upstanding lugs 37 at either side thereof to which is pivoted the operating member 38. The latch 35 has a notch 39 therein into which the operating member 38 is arranged to fall by gravity, thereby locking the latch 35 immovable with the lever 21, as is shown in Figs. 3 and 4. The latch 35, to prevent it from moving laterally out of the slot 34, has an upturned end 40 which holds it therein.

Connecting the coupler centering device and the coupler is a centering rod 41, one end 42 of which is bent downwardly to engage the elongated slot 43 in the coupler shank 3 just forward of the vertical aperture 4. The opposite end 44 of the rod 41 is likewise turned downward to engage in the elongated slot 45 in the latch 35.

As is indicated above, in operating my improved device on railroads in which rather extreme conditions of track curvature are met, I have found it desirable to provide centering mechanism for the coupler which permits a free lateral swing within the limits of its automatic coupling range, as is indicated by the lines *a* and *b*, and I have taken care of such condition by providing the slot 45 in the latch 35 of such a length that the centering rod 41 is free to travel until the coupler 2 is swung to the limits of its automatic coupling range to one side or the other without bringing the centering mechanism into operation. When, because of conditions of track curvature referred to above, the automatic coupler is swung outside the automatic coupling range, the end 44 of the rod 41 will come into bearing with one end or the other of the slot 45 in the latch 35, and cause the latch 35 to move with it. As the latch 35 is locked rigidly in the slot 34 of the lever 21 by the operating member 38, which has dropped down into the notch 39 in the latch 35, the movement of the latch in either direction causes the lever 21 to swing to one side or to the other, depending on the direction of movement of the car coupler. Thus, when the lever 21 is pulled toward the sill 50 by the movement of the centering rod 41, the inner follower 29 is held stationary against the shoulder 30 of the base member

18, and the links 24 and the outer follower 27 move toward the sill 50 in unison with the lever 21, thus compressing the spring 28. When the lever 21 is pushed outwardly by the centering rod 41 the outer follower 27 is held stationary by the through bolt 31 and the inner follower 29 moves outwardly with the lever 21, thus compressing the spring 28 against the outer follower 27. As the apertures in the outer ends 25 of the links are elongated, this permits the outward movement of the links 24 relative to the outer follower 27.

As soon as the pressure caused by the rounding of the curve is relieved, the centering mechanism actuated by the spring 28 tends to return the coupler 2 to a normal central position within its normal automatic coupling range.

When it is desired to use the transitional coupling mechanism, in which event it is necessary to swing the automatic coupler 2 to one side so as to permit the pulling hook 8 to be brought into the line of draft, the operating handle 38 is raised, thus elevating it out of the notch 39 in the latch 35, which unlocks the latch 35 from its rigid engagement with the lever 21 and thus permits the automatic coupler to be swung to one side without restraint by the centering mechanism.

When it is desired to re-employ the automatic coupler, the automatic coupler is pulled over within the limits of its automatic coupling range, and the consequent lateral movement of the rod 41 will carry with it the latch into such a position that the operating handle 38 will again drop into the notch 39 in the latch 35 and thus lock the latch 35 and lever 21 together, thereby bringing the centering mechanism again into operation.

The terms and expressions which I have employed are used as terms of description and not of limitation, and I have no intention, in the use of such terms and expressions, of excluding any mechanical equivalents of the features shown and described, or portions thereof, but recognize that various structural modifications are possible within the scope of the invention claimed.

What I claim is:

1. In coupling mechanism, unlike and alternatively used couplers laterally displaced from each other, a pivot pin, each coupler transmitting stresses to a railway vehicle through the said pivot pin, each coupler being in non-coupling position when the other is in use, and a coupler centering device connected to one of said couplers arranged to control the movement of said coupler, the said coupler being free without restraint from said centering device to move laterally during normal coupling movements, and means for operatively dis-

connecting the centering device from the said coupler when the other coupler is in use.

2. In coupling mechanism, unlike and alternatively used couplers laterally displaced from each other arranged to transmit stresses to a railway vehicle through a common pivot pin, each coupler when in coupling position being arranged to hold the other in noncoupling position, one of said couplers being an automatic coupler movable laterally during coupling operations with a like coupler, a coupler centering device connected to the said coupler, means for operatively disconnecting the centering device when the other of said couplers is in use, and automatic means for reconnecting the centering device and the first mentioned coupler when the said coupler is returned to coupling position.

3. In coupling mechanism, unlike and alternatively used couplers laterally displaced from each other arranged to transmit stresses to a railway vehicle through a common pivot pin, each coupler when in coupling position being arranged to hold the other in noncoupling position, one of said couplers being an automatic coupler movable laterally during coupling operations with a like coupler, a coupler centering device connected to the said coupler, means for operatively disconnecting the centering device when the other of said couplers is in use, and automatic means for reconnecting the centering device and the first mentioned coupler when the said coupler is returned to coupling position, the centering device being adapted to control the radial movement of the said coupler beyond its coupling range and to return it to the coupling range.

4. In coupling mechanism, unlike and alternatively used couplers laterally displaced from each other arranged to transmit stresses to a railway vehicle through a

common pivot pin, each coupler when in coupling position being arranged to hold the other in noncoupling position, one of said couplers being an automatic coupler movable laterally during coupling operations with a like coupler, a spring operated coupler centering device mounted on the vehicle, and operating mechanism whereby the centering device and the shank of the automatic coupler may be operatively connected and disconnected.

5. In coupling mechanism, unlike and alternatively used couplers laterally displaced from each other arranged to transmit stresses to a railway vehicle through a common pivot pin, each coupler when in coupling position being arranged to hold the other in noncoupling position, one of said couplers being an automatic coupler movable laterally during coupling operations with a like coupler, a spring operated coupler centering device mounted on the vehicle, and a lever arranged to effect an automatic connection between the centering device and the automatic coupler when the latter is in use, the said lever upon actuation being also arranged to operatively disconnect the said device and the said automatic coupler when the other coupler is in use.

6. In coupling mechanism, unlike and alternatively used couplers laterally displaced from each other, one of said couplers being of saddle shape and mounted upon the other and each being in non-coupling position when the other is in use, a coupler centering device connected to the second mentioned coupler arranged to control the movement of said coupler, and means for operatively disconnecting and connecting the centering mechanism and the said coupler.

JOHN WILLISON.
